UNITED STATES PATENT OFFICE.

WARREN F. DREW, OF SACRAMENTO, CALIFORNIA, ASSIGNOR OF ONE-HALF TO FRANK G. SNOOK, OF SACRAMENTO, CALIFORNIA.

ADJUSTABLE CRUTCH.

SPECIFICATION forming part of Letters Patent No. 705,741, dated July 29, 1902.

Application filed November 4, 1901. Serial No. 81,012. (No model.)

To all whom it may concern:

Be it known that I, WARREN F. DREW, a citizen of the United States, residing at Sacramento, county of Sacramento, State of California, have invented an Improvement in Adjustable Crutches; and I hereby declare the following to be a full, clear, and exact description of the same.

My invention relates to an improvement in crutches and of the parts and the constructions and combinations of parts hereinafter described and claimed.

Referring to the accompanying drawings, Figure 1 is a side view of my invention. Fig. 2 is an enlarged horizontal section on the line $x x$, Fig. 1. Fig. 3 is a vertical section of the clasp, collar, and plate. Fig. 4 is a portion of a perspective view of Fig. 2. Fig. 5 is a horizontal section of tubular legs for the crutch. Fig. 6 is a portion of a perspective view of Fig. 5.

The legs A of the crutch may be made of metal and wholly or partially tubular, and the upper part 2 may be tubular and slidably 25 adjustable upon the lower part A, with suitable means for locking the two parts at any point of their extension, or the two parts may be made of wood and slidable upon each other, with similar locking devices, the operation being essentially the same in both cases.

As shown in the drawings, my crutch consists of two parts, which are joined together at the bottom to make a single foot, having the usual or any suitable shoe upon the lower end. At a point some distance above the lower end these two parts separate, diverging gradually to a point where the handhold 3 extends across from one to the other, thence converging slightly and connecting 40 with the upper part 2, which extends upwardly to the part 4, which serves as an arm-support and with which the parts 2 are connected.

As shown in Fig. 1, the portions A are made 45 of wood, flattened on the sides contiguous to the portions 2, which extend down over them, following their curvature and being slidable upon the parts A. These parts may be guided and kept together in any suitable manner by 50 bands or, as I have here shown, by longitu-

dinal tongues formed in one face and grooves in the other, as at 5.

The upper ends of the parts A have bands 6 secured to them and of sufficient size exterior to the parts A to allow the parts 2 to slide 55 freely through the guides thus formed. The lower ends of the parts 2 have similar clasps and guides 7 secured to them and slideable over the parts A, thus allowing the crutch to be extended or shortened within the limits of 60 the overlapping sections A and 2.

In Fig. 5 the parts are made tubular, one of the portions A being of smaller diameter than the other and slideable within it. In the present case I have shown the lower portion 65 as being of the smallest diameter and the upper portion of sufficiently larger diameter so that they telescope freely together. In this construction the exterior portion has a longitudinal slot or channel 8 made in one side 70 and of sufficient length to cover the possible adjustments. This slot is sufficiently open so that when pressure is brought to bear upon the outer tube it will be clamped with sufficient friction against the inner tube to firmly 75 lock the parts together. This is done whenever the crutch has been adjusted to the desired length.

In the construction shown in Fig. 1 the two parts A and 2 are inclosed by a band, (shown 80 at 9,) and within this band is the clamp, which rigidly secures the two parts together, which is made as follows: The band 9 is brought together and has a screw-threaded bolt formed or connected with it, as shown at 10. This 85 bolt extends into a correspondingly screw-threaded nut 11, which fits the end of the handhold or grip 3. This grip has a hole made entirely through it, and upon one end is a nut 11, having a right-hand screw-thread, 90 and upon the other end a similar nut has a left-hand screw-thread. The screw-threaded shanks 10 of the clasps 9 are correspondingly right and left threaded, so that when the grip 3 is turned in one direction both the screws 95 will be drawn into the grip and when turned in the opposite direction they will be forced outward. Loosely surrounding these screw-shanks are ferrules or collars 12, the inner ends of which abut against the nuts 11 and 100.

the outer ends against plates 13, which are interposed between the parts A and the ferrules and which are clamped against the wood of the parts A and prevent their being damaged by undue pressure when clamped together. In order to prevent the ferrules from turning, they are slotted and tongues 14 are cut out of the plates 13 and turned up, so as to pass through these slots, as shown, 5 thus preventing the ferrules from being turned around when the friction contact of the nuts 11 is increased. By this construction it is only necessary to turn the grips 3 in one direction to loosen the binding of the 10 parts, and the two parts A and 2 may be slidably moved one upon the other until the proper length of the device has been obtained. At the same time the grips 3 can be correspondingly moved up or down to suit 15 the length of arm of the user, and then by turning the grips in the opposite direction upon the right and left screw-threaded bolts the nuts 11 will be forced against the ferrules or collars 12 and the latter correspondingly 20 pressed against the parts A or the interposed protecting - plate 13 while the band 9, to which the bolts are connected, pulling against the outer surface of the part 2 will clamp the two parts of the crutch strongly together. 25

30 In case of an extremely heavy person or where there is some danger that this clamp will not be sufficient a screw bolt or pin may be put through either of the plates 6 or 7, which clasp the upper or lower ends and 35 junctions of the two parts of the crutch.

When the parts A and 2 are made in the form of tubular metal sections, the outer one being slotted at 8, as previously described, the band 9 surrounds the outer tube, and the 40 screw-threaded bolt 10 forms an extension of

it, as previously described. In this case the end of the collar or ferrule 12 which abuts against the slotted tube 2 is made segmental in shape, so as to partially clasp this tube, and when the parts are drawn together by the 45 turning of the grip 3 the inclosing segment 12 compresses the outer tube and by reason of it being slotted clamps it firmly upon the inner one.

In order to prevent the grips turning backward to release the clamp, a suitable latch or stop may be employed. Such a stop is shown at 16 in the form of a slide on one part adapted to engage notches on the other contiguous part. 50

Having thus described my invention, what I claim as new, and desire to secure by Letters Patent, is—

1. In a crutch, the combination of tubular telescopic leg portions, the outer of said portions being longitudinally slotted, a handhold extending transversely between the legs and having terminal bands inclosing said slotted portions, and clamping mechanism carried by said handhold by which the said slotted 60 portions are contracted and locked upon its respective slidable part. 65

2. In a crutch of the character described, upper and lower members slidably movable to lengthen or shorten the structure, hand 70 grips and clamps controlled thereby to lock the parts together, and locking devices to prevent the clamps being turned backward.

In witness whereof I have hereunto set my hand.

WARREN F. DREW.
